DESIGN FOR A COMBINED ASH TRAY AND HOLDER FOR SMOKERS' ARTICLES

Claude B. Crane, Kansas City, Mo.

Application September 17, 1945, Serial No. 122,139

Term of patent 7 years

(Cl. D85—2)

To all whom it may concern:

Be it known that I, Claude B. Crane, a citizen of the United States, residing at Kansas City, in the county of Jackson and State of Missouri, have invented a new, original, and ornamental Design for a Combined Ash Tray and Holder for Smokers' Articles, of which the following is a specification, reference being had to the accompanying drawing, forming part thereof.

Figure 1 is a top perspective view of a combined ash tray and holder for smokers' articles showing my new design;

Figure 2 is a side elevational view thereof.

I claim:

The ornamental design for a combined ash tray and holder for smokers' articles, as shown.
CLAUDE B. CRANE.
